Application January 18, 1936, Serial No. 60,646

Term of patent 14 years

To all whom it may concern:

Be it known that I, Edward Schultz, a citizen of the United States, residing at Chicago, in the County of Cook and State of Illinois, have invented a new, original, and ornamental Design for Smoking Stands, of which the following is a specification, reference being had to the accompanying drawing, forming a part thereof.

Figure 1 is a side elevation and Figure 2 is a horizontal section on line 2—2 of Figure 1 of a smoking stand exhibiting my new design the

dominant features of which are shown in full lines.

The design consists primarily of a cylindrical head having a circumferential band, as shown, at each of its opposite ends, together with a plurality of widely spaced bars extending longitudinally between the bands.

I claim:

The ornamental design for a smoking stand, as shown and described.

EDWARD SCHULTZ.
